UNITED STATES PATENT OFFICE

AMOS H. CRAWFORD, OF LIVERPOOL, NEW YORK.

BASKET.

No. 900,487.

Specification of Letters Patent.

Patented Oct. 6, 1908.

Application filed October 12, 1906. Serial No. 338,566.

To all whom it may concern:

Be it known that I, AMOS H. CRAWFORD, a citizen of the United States, and resident of Liverpool, in the county of Onondaga, in the 5 State of New York, have invented new and useful Improvements in Baskets, of which the following, taken in connection with the accompanying drawings, is a full, clear, and exact description.

10 This invention relates to the class of baskets especially clothes-baskets or baskets requiring two handles placed diametrically opposite each other on the basket, which are formed from wickers or willows.

15 The object of the invention is to provide a basket which shall be very strong and durable and simple and inexpensive in its manufacture. And to that end the invention consists in the novel construction and combination of the component parts of the basket 20 hereinafter described and claimed.

In the accompanying drawings, Figure 1 is a vertical longitudinal section of a clothes basket embodying my invention; Fig. 2 is a 25 detached plan view of the central supporting-board of the basket; Fig. 3 is an end view of the basket; Fig. 4 is a fragmentary sectional view of the willow portion of the bottom of the basket; Fig. 5 is an enlarged vertical transverse section of the connection of 30 the body of the basket to the bottom thereof; Fig. 6 illustrates a modification of my invention; Fig. 7 is an enlarged inverted plan view of the skeleton frame of the basket, a portion of 35 the bottom board being broken away to show the attachment of the handle-rod to the said board, and indicating by dotted line the outline of the body of the basket; and Fig. 8 is a perspective showing more clearly the 40 construction and attachment of the rods.

One of the salient features of my invention consists in the construction of the bottom of the basket, which bottom comprises a rigid frame composed of a board and spurs attached to said board and projecting horizontally outward from the edges of the board, said spurs being disposed for reception of willows extending around the board and woven alternately across the tops and bottoms of the successive spurs as shown in Fig. 4 of the drawings. I preferably employ nails —b— to serve the function of the aforesaid spurs, said nails being driven into the edge of the board —a— and disposed in a 50 row around the board and with proper spaces between the nails to allow willows to be

woven thereon in the manner above stated and thus form the marginal portion —c— of the basket bottom, the central or main portion of which consists of the board —a—. 60 The nails —b— are disposed in a plane which causes the bottom of the board —a— to project below the bottom of the willow section —c— and allow the board to support the basket on the ground without causing the 65 willow section —c— to come in contact with the ground and become soiled or wet thereby.

The body —d— of the basket is formed from willows woven on willow standards —e— in the usual manner. The lower ends of said 70 standards are bent inward and pass between the woven willows of the bottom - section —c— and are preferably extended to the edges of the central board —a— as illustrated in Fig. 5 of the drawings. 75

—f— represent two metal rods which extend vertically through the wall of the basket and are sustained laterally by the willows woven across the inner and outer sides of the rods. The lower end portions of 80 the rods are formed into U-shaped loops —h— extending downwardly below the willow-bottom of the basket and terminating in inwardly extending prongs —i— around which the willows are woven. The 85 ends of said prongs are inserted into the edges of the central board —a— and are thus fastened to the bottom of the basket and made to contribute to the support of the willow portion of the bottom. However I do 90 not wish to be limited to the aforesaid construction of the lower ends of the rods —f— inasmuch as in some instances the supporting feet may be formed separately and consist of 95 knobs —l— of any suitable material fastened to downward extensions of the rods as represented in Fig. 6 of the drawings.

Inasmuch as clothes-baskets require on opposite ends thereof, two handles as shown in the accompanying drawings, I employ on 100 each end of the basket a pair of metal rods —f— extending vertically through the end-wall of the basket and above said wall, said rods being sustained laterally by the willows woven across the inner and outer sides 105 of the rods as aforesaid. The rods thus sustained constitute metal standards co-operating with the willow standards and serve to stiffen the body of the basket.

What I claim as my invention is:— 110
1. A willow basket bottom composed of a board disposed in a plane below the base of

the body of the basket and constituting the central and main portion of said bottom, rigid spurs projecting horizontally from the edges of the said board, and the marginal portion of the bottom consisting of willows woven on said spurs and supported thereby in a plane above the bottom of the board.

2. A basket having its bottom composed of a board constituting the central section of the bottom, nails driven into the edges of said board and projecting outward therefrom, a marginal bottom-section composed of wickers woven on said nails, and the standards having their lower ends turned inward and passing between the woven wickers of the aforesaid marginal section of the bottom as set forth.

3. A basket having its bottom composed of a rigid central board, nails driven into the edges of said board and extending outward in

a plane above the bottom of the board, a bottom - section surrounding the board and formed from woven wickers receiving between them the aforesaid nails, standards having their lower ends turned inward to the central board and inserted between the wickers of the bottom section, rods extending upward from the bottom of the basket and united above the top of the basket by a transverse portion of the joined rods, a handle embracing said transverse portion, and the lower ends of said rods formed with loops projecting below the wicker portion of the bottom and terminating in inwardly extending prongs fastened to the bottom of the basket as set forth.

AMOS H. CRAWFORD.
